FRED D. ROBB, OF DOTHAN, ALABAMA, ASSIGNOR OF ONE-HALF TO BENJAMIN R. PILCHER, OF DOTHAN, ALABAMA.

AUTOMATIC PNEUMATIC SEMAPHORE AND TRAIN-STOP MECHANISM.

1,302,711.

Specification of Letters Patent.

Patented May 6, 1919.

Application filed June 18, 1917. Serial No. 175,474.

To all whom it may concern:

Be it known that I, FRED D. ROBB, a citizen of the United States, residing at Dothan, in the county of Houston and State of Alabama, have invented certain new and useful Improvements in Automatic Pneumatic Semaphore and Train-Stop Mechanism, and do hereby declare the following to be a full, clear, and exact description of the invention, 10 such as will enable others skilled in the art to which it appertains to make and use the same:

This invention relates to safety railroad block, crossing tracks and grades crossing 15 systems and more particularly relates to an automatic train controlled pneumatic system including a main service air pipe and blocks with semaphores and train stop mechanism.

20 It is one of the objects of the present invention to provide train controlled pneumatic mechanism for setting block signals and controlling train stops in coördination with the setting of the block signals or the 25 reversing of the block signals to indicate a clear track. It is a further object of the present invention to provide a train controlled automatic pneumatic system involving a main air trunk line or service pipe 30 whereby semaphore signals train stopping devices and grade crossing gates may be automatically set by an approaching train or other vehicle on the track. It is another object of the present invention to provide in 35 combination with a continuous air service line a group of blocks and a valve organization capable of being operated by a train or vehicle moving in either direction along the track so that given semaphore may be set 40 by one actuation of the valve organization when the train or vehicle is moving in one direction and another set of semaphores properly adjusted when a train or vehicle 45 is moving in the opposite direction. A further object of the present invention is to provide for the setting of a plurality of semaphores in proper time by the utilization of a single block air line and thereby to prevent the operation of other than the 50 proper semaphores the operation of which is necessary for the giving of a predetermined signal.

With the above and other objects in view as will be clear to those skilled in the art 55 there is illustrated in the accompanying

drawings and described in the body of the specification, one embodiment of the invention in which drawing,

Figure 1 illustrates in perspective, a section of a track with its associated block signals and train stop mechanism and showing a section of the main service line which is extended throughout the track way and is shown as further described in connection with track crossings and grade crossings, 60 and appropriate signal mechanism relative thereto;

Fig. 2 is a perspective view of a section of the track illustrating a grade crossing having gates operatively controlled through the 70 mechanism connected to the main service line;

Fig. 3 is a perspective view showing a section of the railway system illustrating crossing tracks on the same grade with appropriate semaphore mechanism connected to the 75 main service line, also showing the train stop,

Fig. 4 is a vertical central longitudinal section in partial elevation of the valve organization for controlling the operation of a given signal mechanism the parts being in 80 their normal positions; and

Fig. 5 is a similar view with the parts being illustrated in the depressed position permitting the operation of the service cock 85 to supply air to a block pipe;

Fig. 6 is a cross section on Fig. 4 at line 6—6;

Fig. 7 is a detail sectional view of the 90 signal or semaphore actuating motor.

Fig. 8 is a detail sectional view of a form of check valve for controlling the direction of flow of fluid to the semaphore operating motor;

Fig. 9 is a detail sectional view of the main air supply cock; and

Fig. 10 is a detail sectional view of the train stop or brake throwing device.

While the invention as herein illustrated is 100 shown as applied to a single line railroad track 2, it is obvious that the block and stop mechanism is readily applicable to a multiple track system. For the purpose of controlling the movement of trains in either 105 direction along the track 2 suitable semaphores are indicated as mounted upon poles which are grouped or arranged in respective right hand and left hand organization so that the engineers on vehicles proceeding in 110

- one direction will be controlled through the indication of the semaphores on his right hand but it is possible that instead of using lines of right hand poles 3 and left hand poles 4 for instance, the semaphores may be mounted upon a single line of poles on either side of the track to give the desired control of the train in either direction along the track. Trains running in the direction of the arrow R will read semaphores marked 5—5 while trains running in the direction of the arrow L will read semaphores 6—6 and the trains running in either direction are adapted to operate a valve organization to be described more fully hereinafter and each of which involves a cock lever 7 which is adapted to open communication from a main service air line 8 which is adapted to carry pressure of suitable degree this latter being connected by a plurality of branch pipes 9 each of which is connected to the valve casing 10 so that when the lever 7 thereof is thrown as indicated by the arrow r for instance, then air under high pressure is led through a cross pipe 11 to a block air line 12 which is branched at 13 and extends up a pole 4 to the lower end of a cylinder 14 in which there is provided a piston 15 the lower end of which is connected by its rod and an arm (Fig. 7) to a crank arm 16 of the semaphore 6 so that this latter is lowered by the upward movement of the piston 15 while at the same time air under pressure is flowing along pipe 12 in the direction of arrow a where it is diverted by a stop (in the form of a valve 91, Fig. 8) into a pipe 17 which extends up the next pole 4 in advance of the movement of the train this pipe 17 connecting to the respective cylinder 14 so as to discharge air into the upper end thereof and cause the piston 15 therein to move downwardly and swing the semaphore 6 to a horizontal or stop position. In this manner as the train leaves one semaphore 6 it takes the semaphore down and at the same time sets up the next semaphore 6 in advance position in the line of movement of the train against an engineer who may be coming toward the train which has set the signals. In order to protect the rear of the train as this moves past a semaphore station it engages a second valve organization having a cock lever 7^a Fig. 1 which is thrown down and opens communication through the valve casing 10 to a rear block signal line 25 which is connected at the adjacent post 3 to a branch 26 extending up the post so that the air under pressure is delivered into the cylinder 14 to press a piston 15 therein downward and swing the semaphore arm 5 to a horizontal or stop signaling position as the train moves into the block and at the same time pressure is permitted to pass back along the block pipe line 25 to pass up a pipe 27 at the next post from the rear, the pressure

acting on the lower side of the piston 15 to swing the respective semaphore 5 down. In this way the rear of the train is protected by one semaphore 5 and the front of the train is protected by a semaphore 6 against an on- 70

To provide for the reverse control of the right and left hand semaphores 5 and 6 so that a train moving in the direction of arrow L may properly set the semaphores 6 on his right hand to protect the rear of his train and to properly set the semaphores 5 to protect the front of a train the valve organization within the casing 10 is such that when the air service cock lever 7 is thrown as indicated at the arrow 7 Fig. 1 air is applied under high pressure from the main feed line 8 into a pipe line 25^a extending along the track and which is connected to a branch 28 extending up the adjacent pole 3 so that the adjacent semaphore 5 is taken down by the pressure of the air against the lower side of the piston 15 while at the same time air is conducted forwardly in the pipe 25^a and connects with the pipe 26 of the next semaphore post in advance of the movement of the train whereby pressure is applied to the top of the piston 15 and its semaphore 5 is set in blocking position against an oncoming train. In throwing the lever 7 at the position 1, Fig. 1, the train moving in the direction of the arrow L next moves past the adjacent semaphores and engages and throws a lever at 1' the function of which is to connect the high pressure main line pipe 8 with a cross connection 30 Fig. 1 which taps into the block line 12 and from which pressure will flow therein to the adjacent branch 13 which extends up the post 4 and sets the semaphore arm 6 to a block position pressure also extending rearwardly through pipe 12^a to the branch 13 which extends up the next post 4 in the rear of the moving train to take down the respective semaphore. 95

It is one of the important features of the present invention to prevent the flow of the air under pressure beyond predetermined points in the block air lines and to secure this effective control there is illustrated in Fig. 8, at 35 a suitable check valve which will be disposed at joints in the block pipe lines at each of the transverse connections 30 and 11 with the respective pipes 13, 17, 26 and 28 so that air will be prevented from flowing beyond the check valves when moving in given directions to create pressure in the pipes. 100

Another important object of the invention is to provide train stop means automatically operated simultaneously with the setting in the danger or stop position of any semaphore arm 5 or 6 against a train. To that end there is connected to these pipes 13 and 17 and 28 and 26, which control the raising and lowering of the arm respec- 125 130

tively, a pneumatically actuated stopping device comprising as shown in Fig. 10, a plunger 36 having an upwardly extending arm and a piston 37 the latter being mounted in a cylinder 38 having means for connecting at its lower end a pipe for the admission of air to the cylinder 38 and which pipe is connected to those of the semaphore setting pipes of the system so that when the 10 semaphore arm is to be elevated then pressure acts on the piston 37 to cause this to be elevated and project the plunger 36 into operative position so that it will engage any suitable element as a lever indicated at 48 15 connected to the pneumatic air brake system on the moving train. To secure the downward movement of the train stopping device 36, there may be connected to the cylinder 38 one of the pipes as 13 or 28 so that pressure when lowering a semaphore arm will be conducted to the upper part of the casing 38 and thus cause the downward movement of the piston 37 and its plunger 36.

The detail construction of the valve organization is clearly illustrated in Figs. 4, 5 and 6 in which the casing 10 is shown as in the form of an integral casting adapted to be bolted or otherwise suitably secured to one of the track rails T and is provided at 25 its central portion with an inlet 50 to which may be connected a branch pipe 9 from the main feed line 8 or preferably from a receiver or tank 8' introduced in the main feed line for the purpose of providing a reservoir 30 for the compressed air immediately adjacent to the supply branches 9 in the system. The flow of compressed air through the duct 50 is controlled through a supply cock 7' to which the lever 7 is connected. This supply 35 pipe controls flow to diametrically opposite ports 51, 52, which register with respective ports 53 formed diametrically through automatic cut-off valves 54 which are mounted in the respective chambers 54' and are normally pressed downward through suitable 40 springs 56'. The ends of ports 53 in the automatic cut-off valves 54 are adapted to be brought into registration through respective passages 55' with ducts 55 formed in 45 the periphery of automatic block throttle valves 56 which are mounted in respective chambers 57 and which are suitably connected by shanks or stems 58 to a superposed head plate 59 which is mounted in the valve 50 casing 10 for vertical movement relative thereto when it is engaged by the wheel of a vehicle running on the track T. When the head plate 59 is depressed the piston valves 56 are forced downwardly in their respective 55 chambers 57 so that the ducts 55 are brought into registration with ports 55' formed in the casing between the chambers 55 and 57 on each side of the supply cock 7'. The result of this is to bring the ducts 60 51, 53, 55' and 55 on both sides of the cock

into registration and as the upper end of the lever 7 was left exposed by the downward movement of the head 59 this lever will be engaged by the wheel running over the head, and tilted to the position indicated 70 in Fig. 5 whereby air will be permitted to flow past the cock 7' into the registering ducts and around in registered piston port 55 Fig. 5 this port being adapted to communicate with an outlet formed in the outside wall of the casing 10 in a position symmetrical with the outlet indicated at 60 Fig. 5 the air passing down through the outlet 60 to a passageway 61 and thence up through a duct 62 where it reacts upon the lower side 80 of the piston 54 and this is lifted by the air pressure when reaction through the semaphore block mechanism is sufficient to overcome the pressure of the spring 56'; it being understood that air passes from the duct 61 outwardly through a pipe as 80 connected thereto and which leads to one of the semaphore operating motors. Upon upward movement of the piston valve 54, it carries a duct or port 63 into registration with a port 64 in the adjacent wall of the casing and which communicates with a port 65 (Figs. 5 and 6) formed in the adjacent portion of the throttle valve 56. Air pressure accumulating beneath the piston 56 reacts thereon and passes through a connecting port or passageway 66 to the other side of the valve casing where it reacts simultaneously on the other piston 56 and thereby the pistons with the valve head 59 are caused to be returned to the normal uppermost positions. As soon as this upward movement of the depressed pistons 54 starts the ports 53 thereof are carried out of alignment with the supply ports 51 and 52 so that air from the main line is cut off in its flow to the ports 55' on either side as the case may be, and as that pressure increases in the line the pistons 54 move up so that one of them which is in operation uncovers a relief vent 70 arranged respective thereto in the wall of the casing 10 whereupon the pressure is permitted to fall in the duct 62 which connects with the block operating pipe line to a sufficient degree as is determined by the strength of the spring 56' which causes the valve 54 to be returned to its lower position still holding in the block line pipe the desired minimum pressure. 95 For the purpose of preventing undue back pressure and tendency of the throttle valves 56 to rebound owing to air cushion therebelow, these valves are provided with relief ports 71 adapted to register with ports 72 which lead into chambers 73 at each end of the valve casing and in which the air escaping from below the pistons 56 is trapped while the pistons are down but upon the upward movement of these pistons the ports 72 are covered and ports 74 in the walls of 100 105 110 115 120 125 130

the chambers 73 are brought into register with vent ports 75 in the pistons when these latter are in their upper most positions thus exhausting the chambers 73 through the tops 5 of the pistons.

In order to prevent objects from falling through the aperture provided in the head plate 59 to receive the cock lever 7, the latter is extended through a guard plate 80 which 10 is slidably mounted in a recess 81 formed in the valve head 59. It is desirable that the valve lever 7 be maintained in a neutral position to cut off flow to the ports 51 and 52 of the valve casing when the valve head 15 59 is in its upper position and to positively prevent accidental or mischievous movement of the lever, and this is accomplished through a suitable link train or other appropriate means connected to or controlled by 20 the valve head 59 so that when the latter is depressed the lever 7 is relatively unlocked and when the valve head 59 is in elevated position it is again locked. A suitable means for accomplishing this is illustrated as comprising a pair of locking levers 83 which 25 are connected respectively to links 84 these in turn being connected to crank arms 85 which are pivoted on the top of the valve casing the cranks 85 being connected by 30 links 86 to the bottom of the valve head 59 in such manner that when the latter is depressed, the levers or cranks 83 are both moved away from the lever arm 7 to permit its subsequent and yielding movement by 35 engagement with a car or engine wheel. Upon return movement of the valve head 59 the locking levers 83 are again thrown against the lever 7 to move this to the normal vertical position and lock it.

40 As shown in Fig. 2, the air main 8 is adapted to be connected to controlling valves as above described which in turn are adapted to control the operation of grade crossing gates G when the track 2 is disposed 45 on the level of a road or highway or street, in this instance the valve organization being connected through a suitable pneumatic motor to which fluid pressure may be supplied by the actuation of the valves, disposed at 50 suitable distances from the grade crossing, by contact with the valve of trains or vehicles moving on the track and approaching the grade crossing.

55 My present invention further contemplates the utilization of the pneumatic system for the setting of semaphores at railroad crossings to prevent collision of trains operating over the crossing tracks and this is illustrated in Fig. 3 in which instance the 60 crossing tracks 2, 2' are each connected to the main feed line 8 and by providing at suitable positions back on each line from the point of crossing control valves as heretofore described then a train first reaching one 65 of the control valves on this line moving

toward the crossing actuates the valve and through a connecting pipe extended across the field or the low ground to the opposite and crossing track may set a stop semaphore thereat and prevent operation of other trains 70 by the interposition of the blocking plunger 36 which will engage a valve lever of the train air brake line.

75 While any suitable form of valve may be utilized for controlling the direction of flow in a common block line so that a semaphore arm may be raised or lowered as desired, there is illustrated in Fig. 8, one form of a check valve comprising a piston 90 arranged in a casing at the foot of one of the pipes 80 extending up the post to a semaphore motor and controlling flow of air through the block pipe 12 for instance. The piston valve 90 is of such proportion and design as to provide a wall 91 on one side to prevent the flow 85 of air continuously through the pipe 12 and forming at its opposite side a side duct opening 92 allowing for the flow of air from that section of pipe 12 thereadjacent to permit air to flow up the pipe 13. The lower end of 90 the piston valve 90 is open to a connecting pipe 11 and has at one side a port 93 which when the piston valve 90 is shoved upwardly by air pressure in the pipe 11 opens communication to the right hand side of the 95 pipe 12, Fig. 8, while the opposite wall of the valve 90 closes communication on the left hand side. When the valve is in the upper position, air is permitted to pass from the pipe 11 into the pipe 13 through means 100 of a yielding check valve 94 mounted in the sliding valve 90, this check valve being designed to prevent the passage of air from the upper end of the check valve 90 downwardly toward and through the port 93. Obviously this type of valve would be so set 105 or arranged in its respective pipings as to control the flow of air in a direction required to govern the operation of a respective semaphore.

110 From the foregoing it will be seen that I have provided a train control valve mechanism which is automatically reset to a normal position and substantially locked therein, by the normal working pressure in the semaphore controlling line which is maintained for instance, at a degree of seventy-five pounds by the relief pistons 54 in their operations. This pressure of seventy-five pounds works upwardly against the bottoms 115 of the pistons 56 which sustains the head block 59 of the valve in uppermost normal position and at the same time locks the lever 7 of the main supply cock 7^b in vertical position and prevents it from being tampered with, through means of the locking levers 83.

120 While the pressure on each side of the pistons in the semaphore operating motors is substantially equalized the semaphore 125

arms may be prevented from accidental movement either by friction of the piston in its cylinder, or by any other suitable and simple device, as for instance a spring or 5 brake member so disposed with relation to the semaphore arm as to automatically, temporarily lock it in its desired upper or lower position.

Briefly the operation of the system is as 10 follows: Air pressure being maintained in the trunk line 8, which is connected to the main cock 7^a of each semaphore, if the lever 7 of a cock is thrown in the direction of arrow *r* Fig. 1 air will pass through the 15 spring pressed cut-off valve 54 on one side of the cock, thence through the lateral port 55 in the respective and depressed piston valve 56, to port 60 and by pipe 11 to a branch valve 35 at the joint of pipe 13 and 20 forward pipe 12. The valve 96 rises and delivers to forward pipe 12 to put up the next front semaphore 6, and to pipe 13 of the adjacent semaphore to take it down. Meanwhile valve 35 prevents flow rear- 25 wardly in line 12. When the pressure in this related group is equalized the cut-off valve is lifted against its spring 56' (Fig. 5) and the head 59 restored by pistons 56. This cycle is repeated as to every coördinate 30 pair of semaphores as the vehicle trips the various levers 7 in its path in either direction of travel. Thus having set the next advance signals by tripping lever 7 at 7' then as the actuating vehicle passes an adjacent semaphore a lever 7^a is tripped and pressure is admitted by the respective valve set to branch valve 35 thence up pipe 26 to set signal 5 and back through pipe 25 to take down the next rear semaphore (not 35 shown).

Each main cock is related to a trio of semaphores namely the one adjacent, and the next nearest along the track in either direction so that a vehicle moving in one 45 direction sets (up and down) one pair and when moving in the other direction sets (up and down) another pair of which that semaphore adjacent to the main cock (or between the other two) forms one.

50 What is claimed as new is:—

1. In a pneumatic block system for rail-ways, a track; a semaphore; a double acting motor connected thereto; a main for air pressure; and connections between the op-55 posite ends of said motor and the main, in- cluding a vehicle controlled valve adjacent the track for admitting fluid pressure to op- posite sides of the motor through said con- nections and sets of automatic control valves 60 interposed in the connections and between which the aforesaid valve is arranged so as to admit fluid to either.

2. In a pneumatic block system for rail-ways; a track; a semaphore; a double act-65 ing motor connected thereto; a supply main;

and opposite ends of the connections be-70 tween said main and motor, including a valve operative by movement of a vehicle in one direction, to permit setting of a sema- phone and by reverse movement to take down a semaphore.

3. In a pneumatic block system for rail-ways; a track; a semaphore; a double act-75 ing motor connected thereto; a supply main; and connections between said main and op- posite ends of the motor, including a valve 80 operative by movement of a vehicle in one direction, to permit setting of a semaphore and by reverse movement to take down a semaphore.

4. In a pneumatic block system for rail-ways; a track; a line of semaphores; a dou-85 ble acting motor for each semaphore; a sup- ply main; connections between said main and the motors, and vehicle controlled means 85 for setting semaphores in one coördinate re-lation in pair when operated by a vehicle moving in one direction and for reversing the position of the same pair.

5. In a pneumatic block system for rail-ways; a track; a line of semaphores; a pneu-90 matic motor for each semaphore; a supply main; connections between said main and the motors, and vehicle actuated valves for admitting pressure from the supply means 95 to said connections for setting semaphores in one coördinate relation in pair when operated by a vehicle moving in one direction and for reversing the position of the same pair.

6. In a pneumatic block system for rail-ways; a line of semaphores; a pneumatic, double acting motor for each semaphore; a supply main, connections between said main and each motor, including successive train 105 actuated valves for simultaneously reversing semaphores of a respective pair in the direction of movement of a vehicle on the rail-way and a pair of auxiliary, yieldable valves coördinate to each main valve and to either of which auxiliary valves of a pair fluid is served by the relative main valve.

7. In a pneumatic block system for rail-ways; a line of semaphores; a motor for 110 each semaphore; a constant pressure air sup- ply main, connections between said main and each motor, including successive train controlled reversible valves for simultane-ously reversing semaphores of a coördi- nate pair in the direction of movement of 115 a vehicle on the railway, said valves being operative by a reverse movement to control simultaneous reversing of respective semaphores of another pair, one of which is of the aforesaid pair.

8. In a pneumatic block system for rail-ways; a track; a constant pressure air sup-120 ply main therealong; two series of sema- phores, one for each direction of vehicle travel, a motor for each semaphore; two 125

series of main double throw valves connected to the main, one series operable to control semaphores in the direction of travel and the other to control semaphores in the rear 5 of the vehicle and operative by a vehicle to control the setting of semaphores of the two series vice versa, a pair of auxiliary valves, for each main valve, and connection between each auxiliary valve and a pair of the semaphores.

10. In a pneumatic system for railways; a track; a supply main therealong, two series of semaphores, one for each direction of movement of a vehicle on a track; a pneumatic motor for each semaphore and connection between the main and each motor, and a vehicle-controlled valve for each semaphore for setting coördinate or related semaphores in one position when the actuating vehicle is 15 moving in one direction and for reversing the adjacent related semaphore when the vehicle is moving in the opposite direction.

10. In a pneumatic block system for railways; a track; a supply main therealong; 25 two series of semaphores, one for each direction of movement of a vehicle on the track; pneumatic motors for the semaphores, and connections between said main and each semaphore motor, and vehicle controlled 30 valves adjacent the track, one set of the valves coördinate pairs of said semaphores to give block signals ahead when a vehicle is moving in one direction, and for another set controlling the position of other related semaphores when a vehicle is actuated in an opposite direction.

11. In a pneumatic block system for railways; a supply main for air under pressure; a line of semaphores; a motor for each; differential fluid pressure connections between 40 said main and opposite ends of each motor; and a reversible train operated valve for each motor whereby their semaphores are set or reversed through said connections.

45. 12. In a pneumatic safety signal system, a track; a series of semaphores arranged therealong and a pneumatic motor for each; a set of track crossing semaphores and pneumatic motors therefor; an air supply main common to all said motors, and vehicle controlled 50 valve means for controlling the actuation of said motors by fluid pressure from said main, said means including for each semaphore, a double throw main cock, a set of positively actuated throttle valves; and a set of automatic cut-off valves operated by pressure admitted by the main cock, the cut-off valves acting independently of each other.

60. 13. In a pneumatic safety signal system, a track; a series of semaphores arranged therealong and a pneumatic double acting motor for each; an air supply main common to all said motors; and a vehicle controlled double throw valve for controlling the actuation of

respective motors of the fluid pressure from 65 said main, the valve having a connection to each end of the motor.

14. In a pneumatic safety signal system, a track; a series of semaphores arranged therealong and a pneumatic motor for each; a set of track crossing semaphores and motors therefor; a grade crossing gate or gates and a respective motor or motors; an air supply main common to all said motors; and vehicle controlled means for controlling 70 the actuation of said motors by fluid pressure from said main; and means at each semaphore for setting a vehicle brake system and connected to the respective semaphore controlling means.

80. 15. In a pneumatic signal system for railways, a pneumatic motor and a signal member to be operated thereby; a feed main for air; and a valve organization connecting said main and motor and comprising a casing disposed adjacent to a track, a main cock in said casing adapted to be thrown by a vehicle on said track, a wheel plate in said casing and a piston connected thereto, the casing having an outlet duct controlled 90 by said piston and leading to the motor, and a cut-off valve controlling fluid flow from said cock to the piston controlled duct.

95. 16. In a pneumatic signal system for railways, a pneumatic motor and a signal member to be operated thereby; a feed main for air; and a valve organization connecting said main and motor and comprising a casing disposed adjacent to a track, a main cock in said casing adapted to be thrown by 100 a vehicle on said track, a wheel plate in said casing and a piston connected thereto, the casing having an outlet duct controlled by said piston and leading to the motor, and a cut-off valve controlling fluid flow 105 from said cock to the piston controlled duct, and also controlling return of said piston.

110. 17. In a pneumatic railway signal system, a fluid pressure main; a signal and a motor therefor; and a vehicle actuated valve organization comprising a casing having an outlet connected to said motor, an inlet connected to said main, a vehicle throw cock controlling inlet flow, a vehicle actuated piston valve in said casing controlling flow to said outlet, and automatic means operated by fluid pressure when the cock is open to return said piston.

120. 18. In a pneumatic railway signal system, a fluid pressure main; a signal and a motor therefor; and a vehicle actuated valve organization comprising a casing having an outlet connected to said motor, an inlet connected to said main, a vehicle throw cock controlling inlet flow, a vehicle actuated piston valve in said casing controlling flow to said outlet, and automatic means operated by fluid pressure when the 125

cock is open to return said piston, and control the pressure in the motor line from the casing.

19. In a pneumatic railway signal system, a main for fluid pressure; a signal member and a pneumatic motor therefor; a valve casing disposed adjacent a track and connected to said motor; a main cock controlling flow to the motor; vehicle controlled means for throwing said cock to opposite position to secure double actuation of the motor, vehicle controlled valves for establishing communication between the cock and motor, and pneumatically controlled means controlling communication between said cock and valves. 40
- 10 20. In a pneumatic railway signal system, a main for fluid pressure; a signal member and a pneumatic motor therefor; a valve casing disposed adjacent a track and connected to said motor; a main cock controlling flow to the motor; vehicle controlled means for throwing said cock to opposite position to secure double actuation of the motor, vehicle controlled valves for establishing communication between the cock and motor, and pneumatically controlled means controlling communication between said cock and valves and means controlled by said valves for closing the cock. 45
- 15 20 25. In a pneumatic railway signal system, a main for fluid pressure; a signal member and a pneumatic motor therefor; a valve casing disposed adjacent a track and connected to said motor; a main cock controlling flow to the motor; vehicle controlled means for throwing said cock to opposite position to secure double actuation of the motor, vehicle controlled valves for establishing communication between the cock and motor, and pneumatically controlled means controlling communication between said cock and valves, and means for reducing back pressure against said valves prior to the action of said pneumatic means. 50
- 25 30. In a pneumatic railway signal system, a main for fluid pressure; a signal member and a pneumatic motor therefor; a valve casing disposed adjacent a track and connected to said motor; a main cock controlling flow to the motor; vehicle controlled means for throwing said cock to opposite position to secure double actuation of the motor, vehicle controlled valves for establishing communication between the cock and motor, and pneumatically controlled means controlling communication between said cock and valves and for reducing pressure between said valves and the motor. 55
- 30 21. In a pneumatic railway signal system, a main for fluid pressure; a signal member and a pneumatic motor therefor; a valve casing disposed adjacent a track and connected to said motor; a main cock controlling flow to the motor; vehicle controlled means for throwing said cock to opposite position to secure double actuation of the motor, vehicle controlled valves for establishing communication between the cock and motor, and pneumatically controlled means controlling communication between said cock and valves and means controlled by said valves for closing the cock. 60

In testimony whereof I affix my signature in presence of two witnesses.

FRED D. ROBB.
